UNITED STATES PATENT OFFICE.

JULES HENRI DE SIBOUR, OF WASHINGTON, DISTRICT OF COLUMBIA.

DESIGN FOR A HATBAND.

56,120.

Specification for Design.

Patented Aug. 24, 1920.

Application filed March 31, 1920. Serial No. 370,355. Term of patent 7 years.

To all whom it may concern:

Be it known that I, JULES HENRI DE SIBOUR, a citizen of the United States, residing at the city of Washington, in the District of Columbia, have invented a new, original, and ornamental Design for a Hatband, of which the following is a description, reference being had to the accompanying drawing forming a part thereof.

The figure represents a side view of the hat band embodying my new design emblematic of the American Legion.

The hat band comprises a black band and bow having a plurality of stripes thereon of

the following colors and arrangement; an inner stripe of blue and outer stripes of green and khaki brown, respectively, there being a stripe of rainbow color arranged on each side of the inner blue stripe and between said stripe and the outer stripes of green and khaki brown, respectively.

I claim:

The ornamental design for a hat band, as shown.

In testimony whereof, I affix my signature.

JULES HENRI DE SIBOUR.
